UNITED STATES PATENT OFFICE

WILFRED LEWIS, OF HAVERFORD, PENNSYLVANIA, ASSIGNOR TO THE TABOR MANUFACTURING COMPANY, OF PHILADELPHIA, PENNSYLVANIA, A CORPORATION OF PENNSYLVANIA

PISTON AND CYLINDER CONSTRUCTION FOR MOLDING MACHINES

Application filed February 3, 1928. Serial No. 251,728.

Many molding machines include in their construction a rollover table, and the present invention is a means for rolling over the table with a quick motion at the intermediate portion of its travel and with a relatively slow motion at the end of its travel to the end that the operation of the machine can be speeded up without shocks.

The invention is applicable to various types of machines and it will be claimed at the end hereof.

In describing the invention reference will be made to the accompanying drawings forming part hereof and illustrating one application of the invention, and in those drawings

Figure 1 is an end elevational view partly in section of parts of a molding machine embodying piston and cylinder construction of the invention.

Fig. 2 is a sectional view taken on the line 2—2 of Fig. 1.

Fig. 3 is a central sectional view drawn to an enlarged scale of piston and cylinder construction embodying features of the invention, and

Fig. 4 is a partial section taken in a plane at right angles to the plane of Fig. 3.

In the drawings 2 is an oil cylinder and 1 is an oil piston, and there is packing 20 at the 30 end of the piston and packing 21 at the end of the cylinder. These together with the provision of space between the piston and cylinder provide a chamber 7 between them.

There is a bypass 9 having ports through the 35 cylinder wall and whereof one, 10, is located to be covered by the piston in its innermost position, and whereof the other, 8, is located below the top of the chamber 7 to provide space 11 for trapping oil to check the outstroke of the piston. 15 is a vent opening 40 through the piston wall and it is arranged above the packing 20 thereof to permit slight leakage in order to afford adjustment of the outstroke for a purpose that will be presently 45 described. 14 is a relief passage having a check valve 22 and extending from near the bottom of the cylinder to the top 11 of the chamber 7 to permit instroke of the piston. 23 indicates a rollover table, and a rack 12, 50 meshing with a gear 24 on the trunnion of the

rollover table, serves on the outstroke of the piston, to invert the table. The cylinder 2, is pivotally mounted at 16 in the housing 18.

The mode of operation of the described parts in association with other parts, which will be referred to, may be described as follows:

The piston 1 and cylinder 2 are filled with thin hydraulic oil through the filling plug hole 3 to the level of line H in Figure 3; and air is admitted to the piston through the air pipe 4 and forces the oil out through holes 5 in the baffle cap 6 raising the piston. Oil is trapped in chamber 7, port 8 and by-pass 9 and creates a certain amount of starting resistance. This oil escapes through port 15 into the interior of piston 1 permitting the upward movement of the piston.

As the piston 1 travels up the oil that fills the chamber 7 is forced out through the ports 8 into the by-pass port 9, then back through the port 10. At the top end of the travel of the piston 1, the lower end of the piston cuts off the ports 8 and forms an oil cushion in space 11. This reduces the speed of travel and serves to prevent shock when the stop bolt 25 on the rollover table 23 comes into contact with a corresponding stop 26 on the housing. The vent hole 15 in the piston 1 permits the table 23 to be rolled against stops 26 at a reduced speed without appreciable shock by reason of the oil escaping slowly from the space 11 through the port 15.

The gear rack 12 carries a spring 13 which is compressed at the top end of the travel of piston 1. When air is exhausted from the piston 1 the spring 13 reacts to push the piston 1 down. When the piston moves down oil is admitted to the cushion chamber 11 from the bottom of the cylinder 2 through the relief pipe 14, and check valve 22. Also oil returns through the holes 5 and is prevented from spraying by the baffle plates 6.

58 is an adjusting screw for the purpose of sustaining the weight of the piston and rack so that their weight will not shift the position of the trunnion gear shaft 59 when the rollover table is lifted out of the trunnion shaft during the jarring operation. 60 is a

flexible air hose connection from a pipe line and leading to a valve stand.

It will be obvious to those skilled in the art to which the invention relates that modifications may be made in details of construction and arrangement and matters of mere form without departing from the spirit of the invention which is not limited to such matters or otherwise than the prior art and the appended claims may require.

10 I claim:

1. A rollover mechanism for molding machines comprising an oil cylinder and piston having packing at the end of the piston and at the top of the cylinder to provide a chamber between them, a by-pass having ports through the cylinder wall whereof one is located to be covered by the piston in its innermost position and whereof the other is located below the top of said chamber to provide space for trapping oil to check the outstroke of the piston, a vent opening through the piston wall arranged near the packing thereof to permit the trapped oil to escape slowly while the piston moves up to the end of its travel; a relief passage having a check valve and extending from near the bottom of the cylinder to the top of said chamber to permit instroke of the piston, and a spring for initiating the instroke.
2. A rollover mechanism for molding machines comprising an oil cylinder and piston having packing at the end of the piston and at the top of the cylinder to provide a chamber between them, a by-pass having ports through the cylinder wall whereof one is located to be covered by the piston in its innermost position and whereof the other is located below the top of said chamber to provide space for trapping oil to check the outstroke of the piston, a relief passage having a check valve and extending from near the bottom of the cylinder to the top of said chamber to permit instroke of the piston, and a spring for initiating the instroke.

WILFRED LEWIS.
